A. C. MATHER

UNCOUPLING LINK FOR RAILROAD CARS

Filed Sept. 19, 1923

Inventor:
A. C. Mather

UNITED STATES PATENT OFFICE.

ALONZO C. MATHER, OF CHICAGO, ILLINOIS.

UNCOUPLING LINK FOR RAILROAD CARS.

Application filed September 19, 1923. Serial No. 663,633.

My invention relates to uncoupling links in which a sufficient play or lost motion is provided to prevent damage or breaking while the cars are in use; and the objects of my improvement are, first, to make an uncoupling link which is applicable to the standard construction of uncoupling rod and locking pin; second, to provide a sufficient amount of play or lost motion in the link that the coupler can move the limit of its play without causing any damage; third, to make a simple, cheap and durable construction, and other features to become apparent from the description to follow.

In the construction of a connecting link between the uncoupling lever and the locking pin of a coupler it is desirable to have the same so made that it can readily be applied to the standard makes of couplers; that there is sufficient play or lost motion provided to permit the free movement of the bumper or coupler without causing any damage to the parts; and to make a simple and cheap construction that is readily applied to the standard coupler. All these desirable features are contained in my improved uncoupling link which comprises a flat bar of iron or steel having an elongated opening at one end and a perforation at the other end so provided with a slit that the metal can be bent to permit the threading of the eye of the locking pin onto the hook thus formed and when the metal is bent back to its normal position the locking pin will be permanently attached to the link.

To describe my invention so that others versed in the art to which it pertains can make and use the same I have illustrated it on the accompanying sheet of drawing forming a part of this specification and in which:

Figure 1 is a perspective view of a car coupler attached to the end of a car having my improved uncoupling link attached thereto; Fig. 2 is a side elevation of the uncoupling link, the uncoupling rod and the locking pin connected and in their normal position but detached from the car; Fig. 3 is a similar view showing the relative position of the parts when the coupler is drawn out to the limit of its movement; Fig. 4 is a side or edge view of the uncoupling link detached and Fig. 5 is a plan view of the same.

Similar reference characters refer to similar parts throughout the several views.

The end of a car is indicated at 6, and the bumper and coupler at 7. As is well known the locking pin 8 is in its lower or dropped position when the coupler is locked and is in its upper or raised position when the coupler is unlocked. To raise the locking pin 8, an uncoupling rod 9 is provided having a handle end 10 near the corner of the car and having its other bent end 11 connected to the locking pin 8. As is also well known the coupler 7 is mounted on the exposed end of the drawbar which is mounted to have a certain amount of longitudinal movement and is held in position by suitable springs not shown. In operation when the car is pulled and pushed the drawbar and coupler necessarily move against the tension of the springs so that the position of the locking pin relative to the end 11 of the unlocking bar constantly changes. This changing of the position of the locking pin 8 requires that the connection between it and the end 8 of the unlocking lever be a flexible connection with considerable lost motion, to prevent breakage of the parts.

The extremity of the end 11 is flattened and is provided with a perforation 12, the head of the pin 8 is provided with a perforation 13. The link 14 is provided with an elongated perforation 15 at one end and with a rounded perforation 16 at the other end. The flattened extremity of the end 11 is passed through the elongated perforation 15 and an open ring 17 is placed in the perforation 12 to prevent the separation of the parts and yet permit the end of the uncoupling rod to slide in the elongated perforation 15. The link 14 is provided with a cut or slit 18 into the perforation 16 to form an open ring of the same, having the tongue shaped part 19 which can be bent to one side as indicated by dotted lines in Fig. 4, to enable stringing the eye of the pin 8 onto the same, after which the tongue is bent back to its normal position as indicated by full lines to permanently attach the pin 8 to the end of the link 14. As clearly shown in Figs. 2 and 3, the link 14 is prevented from sliding back over the rod end 11 away from ring 17, by coming into contact with the shoulder 20 formed on the rod by the flattening process.

It will be understood that the size, form and arrangement of the parts may be changed somewhat, without in the least departing from the scope of my invention.

Having thus fully described my invention what I claim as new and desire to secure by Letters Patent of the United States is:—

In a device of the class described, the uncoupling rod a link having its lower end attached to the locking pin of a coupler and its upper end slidably connected to the free flattened end of the round uncoupling rod, said link stamped from a flat piece of metal bent at an angle forwardly at its upper end

and having an elongated slot at the upper end sliding along the flattened end of the uncoupling rod and an eye at the lower end having a cut or slit in order to connect to the locking pin.

In testimony whereof I have signed my name to this specification this 7th day of September, at Chicago, Illinois.

ALONZO C. MATHER.
